Primary Examiner—Doris V. ColesAssistant Examiner—Catherine R. OliverAttorney, Agent, or Firm—Darrell F. Marquette[57] CLAIM

The ornamental design for a golf bag with dual shoulder straps, as shown and described.

DESCRIPTION

FIG. 1 is a front elevational view of a golf bag with dual shoulder straps showing our new design;

FIG. 2 is a side elevational view of the golf bag taken from the left in FIG. 1;

FIG. 3 is a side elevational view of the golf bag taken from the right in FIG. 1;

FIG. 4 is a rear elevational view of the golf bag;

FIG. 5 is an enlarged top view of the golf bag with fragmentary portions of the dual shoulder straps being visible; and,

FIG. 6 is an enlarged bottom view of the golf bag with fragmentary portions of the dual shoulder straps being visible.
